Inventor:

Howard R. Sargent,

by *Alfred L. Davis*
His Attorney.

UNITED STATES PATENT OFFICE.

HOWARD R. SARGENT, OF SCHENECTADY, NEW YORK, ASSIGNOR TO GENERAL ELECTRIC COMPANY, A CORPORATION OF NEW YORK.

PLUG-RECEPTACLE FOR USE WITH RUGS.

1,313,120.

Specification of Letters Patent. Patented Aug. 12, 1919.

Application filed December 6, 1917. Serial No. 205,883.

To all whom it may concern:

Be it known that I, HOWARD R. SARGENT, a citizen of the United States, residing at Schenectady, in the county of Schenectady, 5 State of New York, have invented certain new and useful Improvements in Plug-Receptacles for Use with Rugs, of which the following is a specification.

My invention relates to connectors for electric circuits of the type in which a receptacle is let in flush with a floor and contains main line terminals adapted to make contact with the terminal members of a branch circuit carried by a plug when thrust into conducting relation therewith.

The object of this invention is to provide such a receptacle with improved contact making connections for passing through rugs, carpets and the like in a safe and efficient manner without damage to the carpet.

Where plugs were used with the floor receptacles of the prior art to make connections for a branch circuit, through a carpet, rug or the like, large, unsightly holes must needs be formed or cut in the carpet or rug to admit the plug. This interposition of the rug or carpet interfered with the contacts and repeated removal and attachment of the plug invariably resulted in the defacement or mutilation of the carpet or rug.

My invention is designed to overcome these difficulties and to this end I employ a detachable intermediate contact making device arranged to coöperate with the floor receptacle and to pass upwardly snugly through the rug or carpet and to receive in its end projecting above the carpet the contact making terminals of the branch circuit carried by its plug, thereby avoiding their insertion through the rug or carpet and by reason of its detachability from the receptacle the latter is adapted to be closed flush with the floor surface.

For a more complete understanding of the nature and objects of my invention, reference may be had to the following detailed description when taken in connection with the accompanying drawing in which Figure 1 is a vertical section, partly in elevation, of a receptacle and plug embodying my invention in assembled relation, while Fig. 2 is a section thereof taken at right angles to Fig. 1 showing the parts in detached relation.

Referring now to the drawing, 5 denotes an ordinary floor receptacle having a top-

plate 6 designed to be set flush with the floor and containing an insulating base 7 for the circuit terminals. An intermediate base 8 is adapted to detachably coöperate with the receptacle and positioned below the floor level 60 except for a narrow neck portion 9 passing through a correspondingly narrow hole in the rug or carpet 10 and arranged to receive the contact members of the branch circuit of the separable plug member 11. 65

The base 7 which is made of molded porcelain or other suitable material is conveniently mounted on a U-shaped supporting member 12 the ends of which rest in an annular recess 13 formed in the upper portion 70 of the receptacle 5. The base 7 has secured thereto two spring like terminal contact members 14 and 15 to which leads 16 and 17 from the main line may be secured by binding screws 18 and 19, which leads are shown 75 as entering the receptacle 5 through openings 20. The contact members 14 and 15 are protected by an insulating member 21 surrounding them which is suitably secured to the base 7, as by the screw shown at 22. 80

The intermediate base 8 may also be made of molded porcelain and has narrow rectangular openings or tunnels 23 extending upwardly through the narrow neck 9. In these openings are secured contact members 24 and 25, slightly bowed and each having a downwardly extending prong as shown at 26 and 27 adapted to be brought into contact with the spring contacts 14 and 15 when the intermediate base 8 is put in place. 85

The intermediate base 8 also has secured thereto a perforated supporting plate 28 designed to rest on the top of flush plate 6 when the intermediate base 8 is in place and thus provides a smooth surface and support 95 for the rug or carpet 10 lying over the receptacle as shown in Fig. 1.

The neck 9 of the intermediate base 8 slightly projects above the surface of the rug or carpet 10 when in position and is hence 100 well adapted to receive the projecting contact members 30 and 31 carried on the upper base or cap 11 and without any live metal part being brought into contact with the rug or carpet.

The top plate 6 of the receptacle 5 may have the opening which is formed to receive the intermediate base 8, screw threaded as shown at 33 so that if the intermediate base 8 be removed for any appreciable time, a 110

disk may be screwed into this opening to provide a smooth floor surface.

While I have shown and described a particular embodiment of my invention which is at present the best means known to me for carrying the same into effect, I would have it understood that this is merely illustrative and that I do not mean to be limited to the precise details herein disclosed nor to the choice of mechanical equivalents except as defined in my claims hereunto annexed.

What I claim as new and desire to secure by Letters Patent of the United States, is:

- 15 1. The combination with a receptacle having contact terminals therein, of a plug having projecting contact members, an intermediate device having a contracted neck portion and contact making fingers secured therein arranged to contact with said terminals when the device is inserted in said receptacle, said neck portion arranged to receive the projecting members on said plug, and a radial supporting plate secured to said intermediate device at the base of said neck portion.
- 20 2. The combination with a floor receptacle having contact terminals thereon, of an upper base having projecting contact members thereon, an intermediate base having a neck with tunnels formed therein to receive the projecting members on said upper base, contact making members in said tunnels and secured to said intermediate base having projecting portions adapted to contact with said receptacle terminals, and a plate secured
- 25
- 30
- 35

to said intermediate base, arranged to make a flush surface with the floor when said intermediate base is inserted in said receptacle.

3. The combination with a floor receptacle 40 adapted to receive electric conductors having therein a supporting member, a base thereon, contact terminals secured thereto, and a projecting insulating member, of an upper base adapted to receive a branch circuit cable having projecting contact members thereon and an intermediate base formed with a neck arranged to pass through a rug or the like and having tunnels therethrough to receive the projecting 45 members on said upper base, contact making members in said tunnels and secured to said intermediate base having projecting portions adapted to contact with said receptacle terminals and a plate secured to said 50 intermediate base, arranged to rest upon the floor when said intermediate base is inserted in said receptacle.

4. An intermediate part for flush receptacles comprising an insulating base with a 55 contracted neck portion projecting from its upper end and tunnels extending longitudinally therethrough, contacts secured in the said tunnels and having contact fingers projecting from the lower end of said base, and a radial supporting plate secured to said 60 base about the contracted neck portion thereof.

In witness whereof I have hereunto set my hand this 5th day of December, 1917.

HOWARD R. SARGENT.
